Primary Examiner — Eric L Goodman*Assistant Examiner* — Sarah L Smith(74) *Attorney, Agent, or Firm* — Larry E. Henneman, Jr.; Baker & Rannells, PA(57) **CLAIM**

I claim the ornamental design for a wearable light, as shown.

DESCRIPTION

FIG. 1 is a front perspective view of a wearable light, according to the present invention;

FIG. 2 is a rear perspective view of the wearable light of FIG. 1;

FIG. 3 is a front view of the wearable light of FIG. 1;

FIG. 4 is a rear view of the wearable light of FIG. 1;

FIG. 5 is a top view of the wearable light of FIG. 1;

FIG. 6 is a bottom view of the wearable light of FIG. 1;

FIG. 7 is a first side view of the wearable light of FIG. 1; and,

FIG. 8 is a second side view of the wearable light of FIG. 1.
